UNITED STATES PATENT OFFICE

2,080,235

CONTROL ELECTRODE FOR GAS-FILLED TUBES

Henry M. Smith, Scotia, N. Y., assignor to General Electric Company, a corporation of New York

Application May 2, 1935, Serial No. 19,474

4 Claims. (Cl. 250—27.5)

My invention relates to electron discharge devices of the type wherein a controllable discharge takes place through an ionizable medium. More particularly my invention relates to improvements in electrode structure whereby the initiation of an electric discharge in a gas-filled tube is able to be controlled accurately and dependably.

It has previously been proposed to provide means for shielding the grid member of a controlled discharge type of tube from deposits of electron emitting material and inter-electrodes heat radiation and electrostatic effects. Such arrangements are disclosed and claimed, for example, in copending applications, Serial Nos. 704,503 and 17,765 of O. W. Livingston, assigned to the same assignee as the present application.

It is an object of the present invention to provide improved shielding means which, while fulfilling the function of guarding the control electrode from accumulation of electron-emitting material and from undesirable inter-electrode effects, will not unduly complicate the process of tube manufacture and assembly.

It is a further object of my invention to provide a concentric electrode arrangement which will permit an economical design of parts and accurate and dependable predetermination of operating characteristics. More particularly it is my object to produce a sheet metal grid type of gas-filled tube, in which the possibility of variation from a desired standard of operation is substantially avoided by the rigid construction and favorable inter-relation of the electrode parts.

Other and further objects of my invention will be apparent upon considering the following specification in connection with the appended claims and the accompanying drawing in which Fig. 1 is an elevation partly in section of a tube embodying my improved construction; Fig. 2 is a developed view of the sheet metal member from which the inner shielding electrode is formed; Fig. 3 is a developed view of the grid electrode itself, while Fig. 4 is a perspective view, partially cut away to show in detail the relative arrangement of the electrode parts.

In tubes of the type containing a thermionic cathode, an anode and a gaseous ionizing medium at a pressure sufficient to support an arc-like discharge, the flow of a discharge current between the cathode and anode depends on the presence of a considerable number of ions. To prevent the formation of such ions and the initiation of a discharge, it is possible to use a control elec-

trode or grid held at some predetermined potential. This grid operates to diminish the velocity of the electrons drawn from the cathode by the anode potential to an extent sufficient to prevent ionization of the gas from taking place. As the voltage of the control member or grid is varied, it will be found that for a given condition of the tube there is some critical voltage which will just permit the tube to start. Once current flow has commenced, however, the presence of large numbers of ions serves to neutralize the electrostatic effect of the grid and to make cessation of current dependent only on a reversal of anode potential.

This characteristic property of a gas-filled tube gives it unique value as an electronic valve or relay and has led to its application in widespread fields. Due to the fact that many of the uses to which this type of tube is put demand exacting accuracy and dependability of operation, it is of extreme importance that the critical grid voltage which will cause breakdown of the tube shall not vary either with time or with conditions of operation. Unfortunately, however, a number of factors are always present which tend to make unlikely this desired uniformity of operation. Among them is the well-known phenomenon of grid emission, consisting of the generation of electrons from the surface of the grid member. With a clean cold grid this effect is of slight importance, but if the grid becomes coated with impurities and is raised to an elevated temperature by radiation from the cathode or anode, a sufficient emission may take place to cause breakdown of the tube. This is, of course, due to the fact that the emitted electrons act on their way to the anode as ionizing agencies and cause the fulfillment of the conditions which render the tube conductive.

This undesirable situation is of frequent occurrence in gaseous tubes as at present constructed due in part to the fact that the usual cathode, coated with electron emissive material, is apt to have its surface substances thrown off in considerable quantity. This may be attributable either to pure heat vaporization or to the familiar effect known as sputtering, caused by ionic bombardment of the cathode. The ejected material tends to be collected by the grid surface which, when highly heated by radiation from the cathode or anode, acts as a sort of secondary electron source in the manner described above. Under certain conditions it is also possible for the grid to receive electrons emitting material from the anode as well as the cathode. This situation arises when a deposit of such material is

first accumulated on the anode either by the processes of manufacture or during actual use, and in the further operation of the tube is regenerated by heat in such fashion as to be passed on to the grid.

A further objectionable circumstance which may render the gaseous tube conductive at an undesired time is the electrostatic effect of the anode field, which may be variable in extent with the potential impressed upon the anode. When the use to which the tube is to be put requires, as is frequently the case, that it be placed in a relay circuit which is subject to transient voltages, a steep wave front surge may be impressed on it at any moment. If this surge is of sufficient magnitude, the grid may be so affected by the anode field as to cease to perform its normal restraining function and the tube may "fire". In tubes of the high vacuum type such an unrepeatable inter-electrode disturbance would be of little significance since its effect would vanish almost immediately. In the gaseous tube, whose principal function is an initiating one, an unforeseen discharge may set in operation a series of events whose effects will be lasting and disastrous.

Referring to the device shown in Fig. 1, I have shown a sealed envelope 1 of the usual type having at its base a reentrant stem 2 which terminates in a press 3 adapted to furnish a support and seal for incoming current leads. The upper section of the tube 1 has a reduced portion or thimble 4 which, as hereinafter explained, makes possible a greater measure of support for the electrodes contained within the tube. The envelope 1 is adapted to contain an ionizable medium which may consist of an inert gas such as argon, at a pressure from 1 to 500 microns or caesium or mercury vapor. If mercury or caesium is the medium selected, a proper vapor pressure may be maintained by a small quantity of such medium placed in the bottom of the tube.

A substantially cylindrical anode 5 is provided, which may be of any suitable material such as molybdenum, graphite or carbonized nickel, and which in cooperation with the cathode member 7 is adapted to bear the main discharge of the tube. The cathode 7 may consist of a directly heated spiral filament, but may alternatively comprise a straight filament or one of the various indirectly heated cathode forms now in general use. It is coated or otherwise suitably treated with an electron-emissive substance such as barium oxide which when heated is able to afford a sufficient supply of electrons to ionize the gaseous medium in the tube. Both the cathode and anode are supported at top and bottom by insulating mica disks 8 and 10, respectively, which also serve to space and support the remaining electrode members in axial and transverse alignment. The upper disk 8 is of such size as to bear laterally upon the wall of the envelope 1 at its reduced portion 4, thus affording the electrodes considerable protection against lateral displacement.

Heating current from a suitable source (not shown) is delivered to the cathode filament by means of lead-in wires 11 which pass through the press 3, and one of which also serves to bear the main discharge current. A return path for the discharge current is provided through a vertical rod 9 whose lower portion 16 is connected by welding or otherwise to a horizontal extension of lead-in wire 12. The support 9, along with a corresponding supporting member 6, is also used to secure the anode to the insulating disks 8 and

10. Upon a depending extension 13 of the lead-in wire 12 there is mounted a small capsule 14, having an orifice therein (not shown) and adapted to contain a chemically active material, such as barium or strontium, which may be in the form of a relatively stable alloy such as is produced by combination with aluminum. During the course of manufacture the capsule 14 is heated by an external source of energy which may consist of a high frequency induction coil, and the barium or other corresponding material is vaporized into the tube where it operates as a getter to clean up undesirable occluded gases.

Intermediate the cathode and anode and presenting its lateral surfaces to them is mounted a cylindrical grid member 15 which, as is more adequately shown by Figs. 3 and 4, consists of circumferentially extending imperforate sections 18 spaced by punched-out sections 19 and vertically connected by strips 28. This grid electrode, which may be of any suitable conducting material, is supported at the top and bottom by the mica disks 8 and 10 and is connected to a lead-in conductor 31 which passes out through press 3 and stem 2 of the tube. By means of this connection the grid can be maintained at a desired constant or variable potential to restrain or permit the initiation of an ionizing discharge between the cathode 7 and the anode 5 in a manner well understood in the art.

In addition to the discharge bearing electrodes 5 and 7 and the grid 15, which constitute the usual electrodes employed in gaseous tubes, a cylindrical shielding electrode member 20 is placed surrounding the cathode 7 and between it and the grid 15. This may be of metal or other conducting material and is similar in shape and appearance to the grid itself, but, as shown in Fig. 2, has punched-out portions 22 which are of appreciably smaller area than the punched-out portions of the grid electrode. Consequently, both the circumferentially extending sections 21 and the vertical connecting sections 25 present a greater surface to the cathode than do the corresponding portions of electrode 15. Otherwise expressed, the imperforate portions of electrode 20 are of at least as great area as the corresponding portions of control electrode 15 and are positioned to intercept a direct projection of the surface of the latter on the cathode member. It is, therefore, apparent that any particles of solid material vaporized or sputtered from the surface of the cathode and traveling in straight lines will be prevented from reaching the solid portions of the cylinder 15. For this reason there will be little or no tendency for the control element to become coated with electron emissive substances which might seriously heighten the effect of grid emission and lead to a change in the control characteristic of the tube. In addition, the control electrode is adequately hidden from heat radiations from the cathode 7 so that any inherent electron emitting properties which may exist in the control electrode will be reduced to a minimum. With certain special circuit arrangements in which the cathode potential is apt to be varied over such a range that its electrostatic field might adversely affect the grid member, my improved shielding means has the additional virtue of blocking all lines of electrostatic force which proceed normally from the cathode surface.

A lead-in conductor 35 is brought through press 3 and connected in any desired manner to the shielding cylinder 20, whereby it may be held at any desired potential. While it is true that

for most purposes it will be found convenient to maintain the shield at a constant voltage, it is also possible and is included within the scope of my invention to use a variable voltage which may 5 impart an additional controlling function to cylinder 20 without impairing its effectiveness as a shield.

While the advantageous results contemplated by my invention may be largely obtained by the 10 use of a single shielding electrode such as that just described, further and additional advantages may accrue from the use of a second shielding cylinder interposed between the control electrode 15 and the anode 5. Such a second shielding electrode, numbered 23, is shown in Figs. 1 and 4 and is of a construction similar to that of the shielding member 20 but, of course, is proportionately increased in circumference. As in the 15 case of the electrode 20, electrode 23 consists of solid circumferential portions 24 spaced by punched-out areas 26 which are radially aligned with the similar perforations of the control electrode 20 and supported by intermediate connecting portions 32 wider than the connecting portions 25 of the control electrode. Since, as is clearly shown in Fig. 4, this second shielding element is also of such size as to intercept a 20 projection of the control member 15 on the surface of the anode 5, it will serve to cut off heat radiations proceeding from the anode. In the same way it will intercept or materially reduce the anode electrostatic field which tends to reach into the control electrode space and interfere with the normal operation of the tube. In this way 25 those grid emission effects which are blamable on the anode as well as accidental tube discharges due to steep wave front transient surges are effectively prevented. Electrode 23 is shown as being electrically connected to electrode 20 by a bridging connection, but it may alternatively be provided with a special lead-in wire by means of which it can be connected to an external source of potential either constant or variable.

Fig. 2 shows in developed form the sheet metal 30 member which is used in the formation of the shielding electrode 20. It will be readily apparent how it is possible to take a solid sheet of metal and in a single operation punch out or otherwise remove rectangular sections 22 of any predetermined size. After the punching operation, the sheet may be rolled into a cylinder 20 by suitable machinery, and its edges 33 and 34 lap welded or otherwise secured together. In this manner an exceptionally durable and accurately proportioned electrode may be made.

Fig. 3 shows a similar developed view of the main control electrode itself. This can be punched, rolled and welded into a cylinder, as explained above, and placed concentrically with the cylinder 20. It is an extremely important advantage of this type of construction that the relative areas and positions of the punched sections can be predetermined with any desired amount of accuracy. Consequently, the dimensions of the various parts may be specified with a degree of fineness sufficient to guarantee the optimum amount of shielding with a reasonable certainty that variations in assembly will not be great enough to impair the control constants of 45 the tube. Furthermore, due to the inherent rigidity of the finished electrodes and the secure manner in which they may be mounted between insulating disks 8 and 10, a large measure of insurance is provided against an accidental displacement or distortion of parts which would re-

sult in an alteration of the tube characteristics.

It is not necessary for the purpose of my invention that the electrodes 5, 15, 20 and 23 should be exactly cylindrical, and in using this term in the appended claims it is intended to cover all 5 equivalent constructions in which the electrodes shall be of the laterally enclosed type. Furthermore, for many purposes some departure from an absolute concentricity of parts will prove permissible and the use in the claims of the word 10 "concentric" is to be understood as including all such variations.

While I have shown a particular embodiment of my invention, it will of course be understood that I do not wish to be limited thereto since many 15 modifications in the structure may be made, and I contemplate by the appended claims to cover all such modifications as fall within the true spirit and scope of my invention.

What I claim as new and desire to secure by 20 Letters Patent of the United States is:

1. In an electric discharge device containing an ionizing medium, a discharge-receiving electrode producing electrostatic and heat radiation effects, a cylindrical sheet metal control electrode 25 concentric with said discharge receiving electrode, a cylindrical sheet metal shielding electrode between said discharge-receiving and said control electrode, and means rigidly supporting said cylindrical electrodes in coaxial and transverse alignment, said cylindrical electrodes being provided with radially aligned perforations of predetermined size relation, the imperforate portions of said shielding electrode being of at least as great 30 area as the imperforate portions of said control 35 electrode and positioned to insure effective shielding of the control electrode from said electrostatic and heat radiation effects.

2. In an electric discharge device containing an ionizing medium, a cathode member, a cylindrical anode member surrounding said cathode member, a metal control electrode cylinder disposed between said members, a metal shielding cylinder between said control electrode and one of said members, and a pair of spaced planar elements 40 respectively abutting the opposite ends of said anode member and both of said cylinders for maintaining the same in transverse and axial alignment, said cylinders being provided with aligned perforations of predetermined size relation, 45 the imperforate portions of said shielding cylinder being of greater area than the imperforate portions of said control cylinder and so positioned 50 as to intercept projections thereof on the surface of said one of said members.

3. In an electric discharge device containing an ionizing medium, a cathode, an anode mounted concentrically with and surrounding said cathode, a shielded control electrode structure comprising three concentric sheet metal cylinders surrounding said cathode and disposed between the cathode and anode, and means rigidly supporting said cylinders in coaxial alignment, said cylinders being provided with radially aligned perforations of accurately predetermined size relation, 60 the imperforate portions of the inner and outer ones of said cylinders being of such size with respect to the imperforate portions of the center cylinder as to intercept projections thereof on said anode and cathode respectively.

4. In an electric discharge device containing an ionizing medium, a cathode, a substantially cylindrical anode surrounding said cathode, a shielded control electrode structure comprising three concentric sheet metal cylinders surround- 75

ing said cathode and disposed between the cathode and anode, and a pair of plates of insulating material respectively abutting the opposite ends of said anode and each of said cylinders for maintaining the same in axial and transverse alignment, said cylinders being provided with radially aligned slots of similar configuration and accu-

rately predetermined size relation, the solid portions of the inner and outer ones of said cylinders being of such size and so positioned with respect to the solid portions of the center cylinder as to intercept projections thereof on said anode and cathode respectively. 5

HENRY M. SMITH.
